UNITED STATES PATENT OFFICE.

EDWARD O. C. ORD, OF BERKELEY, CALIFORNIA.

GOLD PAN.

Application filed April 21, 1922. Serial No. 555,883.

To all whom it may concern:

Be it known that I, EDWARD O. C. ORD, a citizen of the United States, residing at Berkeley, in the county of Alameda and 5 State of California, have invented certain new and useful Improvements in Gold Pans; and I do hereby declare the following to be a full, clear, and exact description of the invention, such as will enable others skilled in 10 the art to which it appertains to make and use the same.

My present invention relates to improvements in miners' gold pans, and it is especially intended to provide a pan which will 15 be efficient in the removal of the free gold from the sand, and economical in the use of water; and it is intended also to provide a pan which may be used either with the sand wet or dry as conditions may require. 20 As is well known, regions containing gold-bearing sands, or gold bearing rocks which are crushed into sand, are often arid, and in such cases there is generally difficulty in securing an adequate supply of water, and in 25 such cases economy in the use of water is especially desirable, while in all cases it is, of course, important to separate as large a percentage as is possible of the gold or other valuable metal which is to be separated from 30 the sand.

According to my invention I provide a miner's gold pan separated by a central partition into two chambers, the top of the partition being somewhat lower than the side 35 walls of the pan so that the sand and water may be shifted from side to side of the pan in the panning operation, as will be herein-after more fully described.

In addition to the transverse partition just 40 referred to, I may provide one or more additional deflecting ribs, with one or more pockets countersunk in the bottom of the pan to catch the heavier particles, and also to hold the amalgam when used; and I also 45 may provide one or more trough-like guide grooves to permit the pouring out of the residue left in the pan.

My present invention relates more especially to an improvement on the construction 50 shown in my Patent No. 1,419,405, granted June 13, 1922, and entitled Improvements in gold pans.

My invention will be more fully understood after reference to the accompanying 55 drawings, in which like parts are indicated

by similar reference symbols throughout the several views, and in which:—

Figure 1 is a plain view of the pan complete as ready for use.

Figure 2 shows a section along the line 60 2—2 of Fig. 1, and looking in the direction of the arrows.

Figure 3 is a view of the device shown in Fig. 1 as seen from the left of said figure.

Figure 4 shows a section along the line 65 4—4 of Fig. 1, and looking in the direction of the arrows.

Figure 5 shows a section through the handle, the section being taken along the line 5—5 of Fig. 1, and looking in the direction 70 of the arrows; and

Figures 6 and 7 are similar views to Fig. 5, but show different cross sectional shapes of handle.

Referring to Figs. 1 to 5, A represents 75 the main body of the pan which is separated by the rib B into two chambers A' and A², the outer wall of the pan being preferably tapered as at a and provided with a reinforcing bead a'. The rib B is preferably 80 in the form of a flattened wedge, broader at each end than at the center, and having its upper edge b curved downwards towards the center and upwards at each end; the upper portion of said edge b being at sufficient 85 depth below the upper edge of the outer wall of the pan to permit the flow of sand or water from one chamber A' to the other chamber A² without undue tendency of the same to spill out of the pan itself. 90

One end of the rib B is flared outwards to form the curved ears b', which, at their junction with the bottom of the pan, provide corners or pockets a² in which the metal is concentrated. The other end of the rib is 95 provided with somewhat smaller ears b², preferably not so much curved as the ears b', which also form similar corners or pockets a³ to facilitate concentrating the metal.

I also preferably provide a shovel attachment C which is shown in Fig. 2 as integral with the rib B, but may be made separate if desired, and this shovel is provided with the rounded cutting edge c, and may be provided with a hole c⁰ for convenience in hanging the pan on a nail when not in use. 100

Opposite the shovel C I provide a handle D which is rigidly secured to the pan, and for convenience of operation this handle may be provided with a gripping end D' 110

comprising the bent portions d and d' which may be conveniently gripped by the hand of the user.

In addition to the parts just described I 5 may provide on the interior of the pan one or more curved ribs E and E' , which are substantially in the form of an inverted V in cross section, and terminate at the point e adjacent to the middle rib B . These ribs 10 E and E' are in the form of curved horns with the concave side e' next the central rib E , and the convex side e^2 furthest from said central rib E . The said ribs E and E' are symmetrically disposed as shown in Fig. 1. 15 These ribs E and E' may be stamped out of the metal forming the pan, or they may be made of separate pieces and secured in place by soldering or otherwise as preferred. Either or both of the curved ribs E and E' 20 may be omitted if desired.

In addition to the ribs just referred to, I 25 may provide a sunken trap F to receive the concentrate. This trap may be stamped out of the metal forming the pan, or may be applied as a separate piece, as shown in Fig. 4. Instead of the simple flat form of handle shown in Figs. 1 and 2, I may provide a handle of different cross section, such, for instance, as is shown at d^3 and d^4 in Fig. 6, or 30 at d^5 and d^6 in Fig. 7.

It will be seen that the free end of the handle is provided with a resilient hand grip and by using the ribbed or flanged construction shown in Figs. 6 and 7, the stiffness 35 of the handle may be made greater than where a simple flat metal strip is used.

In operation the shovel plate C facilitates the use of the pan in digging into the sand, and the handle D facilitates the operation of 40 the pan both in digging into the sand and in the subsequent separation of the metal from the sand and water, or dry sand, as the case may be.

In operation the pan is filled with sand 45 and is rocked from side to side, and given a swirling motion as well, and the shape of the various ribs facilitates the arresting of the heavier particles of the charge in the lower portion of the pan, allowing the sand 50 and lighter particles to be conveniently removed and the concentrate is finally caught in the sunken trap, from which it may be removed in the usual way.

While I have shown the pan as circular in 55 shape, with the side walls in the form of a frustum of a cone, it will be obvious that changes in configuration may be adopted in the shape of the pan and in the shape of the ribs contained therein. Moreover one or 60 both of the ribs E and E' may be omitted if desired, and also the sunken trap; but I prefer to retain these features in order to have a device that will operate more efficiently and economically.

65 For the intelligent operation of this pan

the following method is pursued: A charge of the material to be washed in a granular form is placed in one side of the divided pan. Water is then put in to cover the sand. The pan is then inclined slightly toward 70 the opposite side and a gentle agitation applied. The sand is settled, the heavier metallic particles falling to the bottom, and as the agitation is continued the lighter sand is quickly washed away and into the other 75 side of the pan until only the heavy metal grains desired are left of the original charge. The pan during this operation is held by the handle. The handle enables 80 reaching for and scooping up sand or gravel with ease and facility. When once charged with sand, this can be shifted all into one side and then the water added.

The shovel-like projection is a point added to enable breaking through snow or any 85 crust in order to get at the gravel beyond the surface and acts as a pick point to get rid of rocks or other undesirable material in the way.

If the pan is of large size for large work, 90 the shovel end serves as a pivotal support and the handle a lever for operation of the pan.

Referring to Figs. 1 and 5, the curved rib B is used as a secondary concentrator of the 95 "tailings" or lighter and washed out sands from the first washing, to ascertain if any losses have occurred of the metals desired retained.

This rib B is also used for testing very 100 small samples when a tablespoonful or two of water only would be required, thus conserving the water when prospecting in arid lands, or the desert regions of California.

The amalgam trap is of the peculiar shape 105 shown in Fig. 4, and placed at the junction of the wall and the floor of the pan and is used, as its name implies, for trapping of the amalgam.

It will be obvious that these and various 110 other changes might be made which could be used without departing from the spirit of my invention, and I do not mean to limit the invention to such details except as particularly pointed out in the claims.

Having thus described my invention what 115 I claim and desire to secure by Letters Patent of the United States is:—

1. A miner's gold pan provided with a rib 120 extending transversely of the pan and separating the same into two oppositely disposed chambers, the said rib being substantially in the form of a flattened wedge having its ends flared outwards to form concaved ears, said rib terminating in a shovel blade at 125 one side of the pan, and a handle extending outwards from the other end of said rib.

2. A miner's gold pan provided with a rib 130 extending transversely of the pan and sepa-

- rating the same into two oppositely disposed chambers, the said rib being substantially in the form of a flattened wedge having its ends flared outwards to form concaved ears, 5 said rib terminating in a shovel blade at one side of the pan, and a handle extending outwards from the other end of said rib, with a sunken trap near the outer edge of one of said chambers.
- 10 3. A miner's gold pan provided with a rib extending transversely of the pan and separating the same into two oppositely disposed chambers, the said rib being substantially in the form of a flattened wedge having its 15 ends flared outwards to form concaved ears, said rib terminating in a shovel blade at one side of the pan, and a handle extending outwards from the other end of said rib, with a curved tapering rib wedge shaped in 20 cross section provided in one of said chambers.
4. A miner's gold pan provided with a rib extending transversely of the pan and separating the same into two oppositely disposed 25 chambers, the said rib being substantially in the form of a flattened wedge having its ends secured to the opposite side walls of the pan,
- said rib terminating in a shovel blade at one side of the pan, and a handle extending outwards from the other end of said rib. 30
5. A miner's gold pan provided with a rib extending transversely of the pan and separating the same into two oppositely disposed chambers, the said rib being substantially in the form of a flattened wedge having its 35 ends secured to the opposite side walls of the pan, said rib terminating in a shovel blade at one side of the pan, and a handle extending outwards from the other end of said rib, with a sunken trap near the outer 40 edge of one of said chambers.
6. A miner's gold pan provided with a rib extending transversely of the pan and separating the same into two oppositely disposed 45 chambers, the said rib being substantially in the form of a flattened wedge having its ends secured to the opposite side walls of the pan, said rib terminating in a shovel blade at one side of the pan, and a handle extending outwards from the other end of 50 said rib, with a curved tapering rib wedge shaped in cross section provided in one of said chambers.

EDWARD O. C. ORD.
